UNITED STATES PATENT OFFICE.

NORMAN T. HARRINGTON, OF CLEVELAND, OHIO.

TOWER.

Application filed June 14, 1920. Serial No. 388,909.

To all whom it may concern:

Be it known that I, NORMAN T. HARRINGTON, a citizen of the United States, residing at Cleveland, in the county of Cuyahoga and State of Ohio, have invented a certain new and useful Improvement in Towers, of which the following is a full, clear, and exact description, reference being had to the accompanying drawings.

This invention relates to load handling systems or apparatus, and more particularly to a system or apparatus of the type wherein the load handling device is movable along a cableway supported at at least one end by a rocking tower. The apparatus or system disclosed herein is particularly well adapted for the use of a single tower wherein the cableway is anchored at one end to a fixed point, its other end being connected to a rocking tower.

One of the objects of the invention is so to support a single rocking tower having a cableway connected to its upper end or portion, as well as the said cableway, as to maintain the distance between such point of connection and the fixed anchor for the opposite end of the cableway substantially invariable. This enables the tower to rock without, on the one hand placing an undue strain upon the cableway and the parts connected thereto, or, upon the other hand, slackening the cableway during such rocking movement, and hence causing the cableway to sag and unnecessarily limit the height of the pile on which the bucket or other load handling device, operates.

As to this object, the invention consists, more limitedly, not only in enabling the tower to rock without varying materially the distance between the anchor for the cableway and its point of attachment to the tower, but without materially varying the distance between the anchor for the guy or hold-down cable or cables and the point of attachment thereof to the tower. In fact, so far as the rocking of the tower is concerned, in connection with the cableway and the guy or hold-down cable or cables, the effect produced is the same as if the cableway and the said guy or cables were continuous, with the upper portion of the tower moving in a bight of the same and maintaining constant the distance of bight from the two anchors.

This result is secured by the manner of

mounting the tower, the arrangement of the anchors for the cableway and hold-down cables or guy, and by giving to the supporting rails for the rocking tower base a configuration which will impart to the point of attachment of the cableway and guy or hold-down cables a movement or movements capable of maintaining the distance from their respective points of attachment to their respective anchors substantially constant.

A further object of the invention is to provide a tower of this character with a counterweight so connected to the bucket or load handling device as to render substantially constant the force or effort tending to overturn the tower, when tilted, as the said bucket or device moves toward and away from the tower. When the bucket or load handling device is near the tower, the counterweight is ineffective; as the bucket or load handling device moves away from the tower, the counterweight passes above its center of gravity and adds its overturning effort to the overturning effort of the bucket, which is diminished by its distance from the tower. The use of this constant overturning effort enables me to employ with the base of the tower a fixed counterweight for the tower, the movable bucket and the cableway, (the sum of whose overturning efforts or moments are constant.)

Referring to the drawings, Fig. 1 represents a side elevation of a system or apparatus embodying my invention; Fig. 2 an end elevation of the same; Fig. 3 a plan view of the same; Fig. 4 a detail in elevation of one of the rails; Fig. 5 a diagrammatic view representing the paths approximately described by the point or points of attachment of the cableway and guy or hold-down cable or cables to the tower; and Fig. 6 a detail in elevation of the tower base and its support.

Describing the various parts by reference characters, 1 denotes generally a tower having a segmental counterweighted base 2 provided with a pair of segmental tracks 3, each cooperating with a rail 4. The segmental tracks or bearings are described from the point 5 as a center. The tracks 4 are carried by a suitable base 6 which is inclined upwardly toward but above the fixed support for the cableway, with the result that the rails 4, which are shown herein as projecting an equal distance above such

base, provide a similarly inclined support for the base 2.

In the drawings, the tower 1 is shown as connected with the counterweighted base 2 so as to rock therewith in the direction of the rails and is also pivotally connected to said base, as indicated at 7, to permit a rocking of the tower in a direction transversely of said rails, for a purpose to be described. The base 2 constitutes a counterweight for the tower, the movable cableway, the load handling device, and the various parts connected thereto.

Located in any convenient position is a drum 8. Wound upon this drum and extending in opposite directions therefrom is a cable 9, the leads or branches of said cable extending each about the lower sheaves 10 and the upper sheaves 11 of a tackle. The lower blocks or sheaves of each tackle are supported in the upper end of a yoke 12, the lower end whereof is supported upon a pivot 13 extending in the direction of the rails 4, the axis of each such pivot being in the same inclined plane (indicated by the line $x-x$) which includes the tops of said rails, said pivots being equidistant from the center of the tower when the latter is in its vertical position. The upper blocks 11 of both tackles are pivotally connected to a common point 14 near the top of the tower, as by means of suitable supporting straps or brackets 15. The drum 8 is preferably disposed midway between the yokes 12 in the central vertical plane through the tower and may be mounted upon any suitable support. By applying power to the drum 8, one part of the cable 9 will be wound upon the drum while the other part is unwound, thus enabling the tower to be rocked in opposite directions upon the rails 4.

For the purpose of holding down the tower and preventing it from being overturned by the cableway and the load thereupon, I employ a guy in the shape of a plurality of hold-down cables. This guy, indicated generally at 16, consists of a plurality of cables each extending about a sheave 17, which sheaves are pivotally supported upon a common axis near the top of the tower, the opposite ends of each cable being anchored each in a yoke 18 having its lower end supported on a pivot 19 extending in the direction of the rails 4 and located in the inclined plane including the upper surfaces of said rails and the pivots 13. The anchors for the cables are located adjacent each to one of the foci of an ellipse which is approximately described by the point of attachment of the sheaves 17 to the tower, as the latter rocks. With this arrangement, assuming that the point of attachment describes a substantially elliptical path during the rocking of the tower, the sums of the lengths of the cables on each side of the

sheaves will be constant, so that the said cables may exercise efficiently their function of holding down the tower and preventing it from falling unduly toward the cableway anchor during its rocking movements.

20 denotes a cableway which is shown as connected at one end to the top of the tower and at its opposite end to a fixed anchor 21, preferably located in a plane at right angles to the center vertical line of the tower when the latter is in its vertical position. The anchor 21 is located below the inclined plane, indicated by the line $x-x$, which includes the tops of the rails 4 and pivots 13 and 19, and which is perpendicular to the vertical center line of the tower a distance to be determined by considerations pointed out hereinafter. Beneath the cableway 20 is the pile of material 22 which is to be operated upon by the load handling device, shown as a bucket 23, mounted on said cableway. This bucket is of ordinary construction and some of the operating lines therefor are indicated at 24 and 25, it being understood that the bucket will be provided with the usual opening, closing and travel lines.

Connected to the carriage for the bucket is a line or cable 26 which extends over a sheave 27 near the upper end of the tower and adjacent to the cableway 20, this line or cable being connected to a counterweight 28, movable in vertical guideways 29 on the face of the tower presented toward the anchor 21, by means of a tackle, the movable block of which is indicated at 30 and the fixed block at 31. The blocks will be provided with a sufficient number of sheaves so that the counterweight may move from the center of gravity of the tower to the upper block 31 as the bucket moves from the upper end of the tower to the anchor 21; in other words, the movement of the counterweight is thus made proportional to the movement of the bucket and will cover, in its range of movement between the center of gravity and the top of the tower, the entire range of movement of the bucket. It will be evident that, as the tower is rocked and the bucket is near the upper end of the tower, it is exerting at such times a maximum force or effort tending to overturn the tower against the resistance of the guy 16 and that, when the bucket is adjacent to the anchor 21, it is exerting a minimum force or effort tending to overturn such tower; also that, in intermediate positions, it is exerting an overturning force or effort which varies inversely with its distance from the top of the tower. The counterweight 28 moves in such manner as to compensate for this variation in the overturning force or effort exerted by the bucket, the joint force or effort exerted by the bucket and the counterweight in a direction to overturn the

tower being constant for the same position of the tower. This enables me to employ the fixed counterweight 2 for the tower, the cableway, and the bucket. The counterweight 28 is adapted to counterbalance the bucket 23 and as much of the load carried thereby as may be advisable.

It will be evident that it is extremely desirable, if not necessary, that the length of the cableway 20 shall be substantially invariable during the rocking of the tower in order to prevent, on one hand, the breaking of the cableway, either of its supports, the hold-down cable, or the tower and, on the other hand, the undue sagging of the cableway which would result in inefficiently limiting the height of the pile 22 on which the bucket operates. At the same time, it is equally evident that the sums of the lengths of the cable branches extending in opposite directions from the sheaves 17 should be substantially constant in order to enable the said cables to support the tower against falling unduly toward the fixed anchor 21. The manner in which I secure this result is shown in Figs. 4 and 5. In the latter figure the tower is indicated as rocking upon the base 6, the point of attachment of the cableway (which may be considered as substantially coincident with the point of attachment of the hold-down cables) being indicated at *a*. As has been pointed out in my application No. 345,755, a point above the center of rotation of a rocking tower supported in the manner shown herein describes a cycloidal curve which closely approximates an ellipse. In order to enable such point to approximate more closely to and substantially coincide with an ellipse, the rails 4 are given a configuration such as shown in Fig. 4. This contour will cause the paths traveled by the points of attachment of the hold-down cables and of the cableway to coincide each substantially with an ellipse. It will be evident that, if the anchor 21 be assumed as the apex of a cone in which the cableway corresponds to a line drawn from said apex to the circumference of the base, and the movement of the tower is such that the point of attachment of the cableway to the tower will describe such circumference, the distance between the points 21 and the point of attachment *a* (and hence the length of the cableway) will be constant as the tower rocks. Such a cone will be described by extending downwardly the central vertical line *y*—*y* of the tower to a point *w* at which a line *w*—*z* drawn at right angles thereto will intersect the anchor point 21, the line *w*—*z* constituting the axis of the cone. However, it is desirable to locate the anchors for the hold-down cables or guy above ground. This I accomplish by the use of a rocking tower wherein the points of attachment of the

cableway and of the hold-down cables are caused to coincide very closely with the circumference of a cone described in the manner set forth. By giving to the rails the configuration such as shown, the sums of the lengths of the branches of the holdown cables will be substantially constant, and the base of the tower can not be lifted from either of its rails during its rocking movements. But the elliptical path described by the point of attachment of the cableway to the tower does not coincide exactly with the circumference of the base of the cone. By pivoting the tower at the point 7, the excess length in the guy or hold-down cables, due to the elliptical path, is allowed to be taken up by the shortage in the cableway. This slight error in the length of the cableway is, however, corrected by the configuration of the rails in which the rocking base 2 is mounted.

It will be noted that the plane in which the tower swings is inclined away from the anchor 21 so that the line *w*—*z* which is perpendicular to said plane extends from a point below the base 6. This enables me to mount the anchors 13, 19 and 21 above or at the surface of the ground and at the same time to approximate the circumference of the base of a cone by the path of movement of the point or points of attachment of the cableway and hold-down cables to the tower.

I have found that, with the point of attachment *a* of a cableway approximately one hundred feet above the base of the tower (or above the base line *b*) the arc of a circle described from a point *w* on the line *y*—*w* about twenty one feet seven inches below said base line and below the center of the tower when the latter is in a vertical position, will intersect the elliptical path *c* described by the point *a*, not only when the tower is in the vertical position, but also when the latter is at its extreme range of movement (about 60° from the vertical) on each side of such vertical position, as indicated at *d*. It will be observed that, between the points *a* and *d*, the divergence between the arc *e* of this circle (a part of the circumference of said cone) and the curve *c* is relatively slight, the arc of the circle being within the curve *c* in such intermediate positions of the tower. I compensate for this difference and bring the path described by the point *a* more nearly into coincidence with the arc *e* by pivoting the tower at the point 7 and by the configuration of the rails. By locating the anchor 21 at the same distance below the inclined plane including the tops of the rails 4 and the pivots 13 and 19, as the distance which the center *w* of the arc *e* is below the base line *b*, as the tower rocks upon its base between the vertical and the extreme positions,

the cableway 20 and the cables constituting the guy act jointly upon the upper end of the tower, causing it to rock upon its pivot 7 and thus force the point *a* to assume a position intermediate the lines *c* and *c*' between the vertical and extreme operating positions of the tower, with the result that the distance between the points 20^a and 21 will be substantially constant and the sums of the two parts of the guy 16 on each side of the sheave or sheaves 17 will also be substantially constant.

To prevent side slipping of the tower base on its support, particularly when in its extreme positions at the right and left of the vertical, I provide the base with gear segments 32 adapted to mesh with racks 33 and the rails supporting the weight of the tower and its parts.

Having thus described my invention, what I claim is:

1. The combination of an angularly movable tower, a cable way attached at one end to the tower and anchored at its other end, the line extending through the anchorage and the center of rotation of the tower forming an appreciable angle with the ground line, and a hold-down cable extending from a bearing point on the tower to points on opposite sides of the central vertical plane on the tower, the anchoring points of the cable way and the anchoring points of the hold-down cable being so disposed relatively to the tower that the distance between the anchoring point of the cable way and its point of attachment to the tower remains substantially inviable, and that the sum of the distances between the anchoring points of the hold-down cable and its bearing point on the tower remains substantially constant for all angular positions of the latter.

2. Device according to claim 1 in which the tower has a segmental rocking base.

3. Device according to claim 1 including a rocking cable extending from substantially a common point on the tower over sheaves anchored on opposite sides of the central vertical plane of the tower, near points representing substantially the foci of an ellipse a portion of which corresponds to the curve described by the said common point during the angular motion of the tower, and a drum upon which the rocking cable is wound.

4. Device according to claim 1 including a connection affording relative angular movement between at least the upper part of the tower and the rocking base in the plane of the cable way.

5. Device according to claim 4 in which the tower is pivotally mounted on the rocking base.

6. Device according to claim 2 in which the anchoring point of the cable way and the tower are so disposed relative to one an-

other that the cable way is substantially the generatrix of a conical surface, the point of intersection of a line from the anchoring point of the cable way perpendicular to the plane of rotation of the tower and the said plane of rotation being the center of a circle a portion of which substantially corresponds to the curve defined by the point of attachment of the cable way to the tower.

7. Device according to claim 6 in which the anchoring points of the hold down cable, the anchoring points of the rocking cable and the surface of the support for the rocking base lie in a plane which is parallel to the said line from the anchoring point of the cable perpendicular to the plane of rotation of the tower.

8. Device according to claim 2 including a support for the rocking base and means on the base or the support for modifying the rocking movement of the base.

9. Device according to claim 8 in which the modifying means consists of rails curved in the direction of the rocking movement.

10. The combination of a tower having a rocking base, a cable way attached at one end to the tower and means for anchoring the other end of the cable way, said means being disposed on a line which is perpendicular to the plane of rotation of the tower and passes through the center of a circle a portion of which substantially corresponds to the curve defined by the point of attachment of the cable way to the tower during the rocking movement.

11. Device according to claim 14 in which the anchoring point is at a point above the horizontal passing through the base of the tower.

12. The combination with a tower, a cable way anchored at one end and attached to the tower at its other end, and means for moving a load along the cableway, of hold-down means and means operative to produce a substantially constant overturning effort on the tower while the position of the load on the cableway varies.

13. The combination with a tower, a cableway anchored at one end and attached to the tower at its other end, and means for moving a load along the cableway, of means for applying a force to the tower tending to increase its overturning effort and means for varying this force inversely as the distance of the load on the cableway from the tower varies, the arrangement being such that the overturning effort of the tower remains substantially constant.

14. The combination with a tower, a cableway anchored at one end and attached to the tower at its other end, and means for moving a load along the cableway, of means connected with the load-moving means for applying a force to the tower tending to increase its overturning effort, the arrange-

ment being such that the said force varies inversely as the distance of the load on the cable from the tower varies.

15. The combination, with a tower, of a cableway connected at one end to the upper portion of said tower, a hold down cable also connected at one end to the upper portion of said tower, the said cableway and cable extending in opposite directions from the said tower, anchors for the ends of said cableway and cable which are opposed to said tower, and means supporting said tower to permit the same to rock in directions transverse to said cableway as well as toward and from the anchors of said cableway and cables.

16. The combination, with a tower, of a cableway connected to the upper portion of said tower, a hold down cable also connected at one end to the upper portion of said tower, anchors for said cableway and cable located on opposite sides of said tower, a load handling device movable along said cableway, means for rocking said tower, and means for supporting said tower whereby the length of the cableway and of the hold down cable will be substantially invariable during the rocking movements of the tower.

17. The combination, with a tower, of a cableway connected to the upper portion of said tower, a hold down cable also connected at one end to the upper portion of said tower, anchors for said cableway and cable located on opposite sides of said tower, a load handling device movable along said cableway, means for rocking said tower, and means for supporting said tower whereby the point of attachment of the cableway to the tower will describe a curve substantially coinciding with the circumference of the base of a cone whereof the cableway anchor is the apex.

18. The combination, with a tower, and means for rocking the same, of a cableway connected to the upper portion of said tower, a hold down cable also connected to the upper portion of said tower and means for supporting the said tower, the said cable and the end of the cableway which is opposed to said tower to preserve substantially invariable the distance between the supports for the said cable and cableway during the rocking movements of the tower.

19. The combination, with a tower having a rocking base, of a cableway connected at one end to said tower, a hold down cable also connected to said tower, a support for said base, anchors for the ends of the cableway and cable which are opposed to said tower, and a connection between said tower and its base for permitting the tower to rock on said base and toward and from such anchors.

20. The combination, with a tower and means for rocking the same, of a cableway connected to the upper portion of said tower, a load handling device movable along said

cableway, and means supporting the said tower and the end of said cableway which is opposed to said tower to preserve substantially invariable the distance between the supports for said cableway during the rocking movements of the tower.

21. The combination, with a tower and means for rocking the same, of a support on which said tower rocks and which is inclined transversely with respect to the rocking movement of said tower, a cableway connected at one end to said tower, an anchor to which the other end of said cableway is secured and located below the plane of such support, and a load handling device movable along said cableway.

22. The combination, with a tower having a rocking base and means for rocking the same, of a support on which said base rocks, a cableway connected at one end to said tower, an anchor for the other end of said cableway, a load handling device movable along said cableway, and a pivotal connection between said tower and its base.

23. The combination, with a tower and means for rocking the same, of a cableway connected to the upper portion of said tower, a load handling device movable along said cableway toward and from said tower, and a counterweight connected to said device and movable with respect to said tower and cooperating with said device to render substantially constant the effort or force tending to overturn said tower through the joint action of said device and said counterweight.

24. The combination, with a tower and means for rocking the same, of a cableway connected to said tower, a load handling device movable along said cableway and toward and from the upper portion of said tower, a counterweight movable along said tower and between the top and the center of gravity thereof, and means for connecting said device and said counterweight to move the counterweight toward the top of the tower as the said device recedes therefrom, and vice versa.

25. The combination, with a tower, and means for rocking the same, of a cableway connected to the upper portion of said tower, a load handling device movable along said cableway and toward and from the upper portion of said tower, a guide extending longitudinally of said tower, a counterweight cooperating with said guides, a sheave connected to the upper portion of said tower, a tackle having its upper block connected to the upper portion of the tower and its movable block connected to said counterweight, and a cable connected to said device and extending over said sheave and about the sheaves in said blocks.

26. The combination, with a tower having a counterweighted rocking base and a support for said base, of a cableway connected

at one end to the upper portion of said tower, a load handling device movable along said cableway toward and from said tower, a counterweight movable longitudinally of 5 said tower and toward and from the top of the same, and means connecting said device and said counterweight whereby the counterweight will be moved toward the top of the tower as the said device moves away 10 from the same, and vice versa.

27. The combination, with a rocking base and a support upon which said base may rock, of a tower pivoted to said base to permit movement of the tower transversely of

the direction of the rocking movement thereof, a cableway connected at its upper portion to said tower, a sheave connected to the upper portion of said tower, a hold down cable extending about said sheave and anchoring the end of the cableway which is opposed to the tower, the support for said base being inclined toward and above the anchor for the cableway, the anchors for the hold down cable being located substantially in the inclined plane including said support. 15
